ARM RESTRAINING STRAP FOR AUTO RACING

Steve A. Bolan, 1925 W. 2nd Place,
Mesa, Ariz. 85201

Filed Aug. 16, 1973, Ser. No. 388,885

Term of patent 14 years

Int. Cl. D2—07

U.S. Cl. D2—381

FIG. 1

FIG. 1 is a perspective view of an arm restraining strap for auto racing showing my new design; and

FIG. 2 is a perspective view thereof in wearing position, the broken line disclosure being for purposes of illustration only.

I claim:

The ornamental design for an arm restraining strap for auto racing, as shown and described.
